UNITED STATES PATENT OFFICE.

SYLVESTER B. McGUNIGAL, OF WASHINGTON, DISTRICT OF COLUMBIA, ASSIGNOR TO THE STONE STRAW COMPANY, OF WASHINGTON, DISTRICT OF COLUMBIA, A CORPORATION OF NEW JERSEY.

TUBE-CUTTING MACHINE.

1,297,203.

Specification of Letters Patent. Patented Mar. 11, 1919.

Application filed July 13, 1917. Serial No. 180,303.

To all whom it may concern:

Be it known that I, SYLVESTER B. McGUNIGAL, a citizen of the United States, residing at #1300 11th street S. E., in the city of Washington, and District of Columbia, have invented certain new and useful Improvements in Tube-Cutting Machines, of which the following is a specification.

The present invention, has reference, generally, to cutting machines; and, the invention relates more particularly, to an improved machine for severing tubes.

The invention has for its principal objects to provide a tube cutting machine which will cut a continuous tube as fed therethrough into a plurality of smaller lengths or sections.

Another object of my invention is to provide means for intermittently moving the cutting mechanism of the machine into and out of engagement with the continuous tube to be severed at predetermined periods, consequently, insuring the production of tubes of approximately uniform length.

The invention also aims to provide a novel cutting mechanism, whereby, the continuous tube when engaged thereby will be cut evenly and clean, tearing of the tube, caused by the motion thereof through the machine and uneven cutting being obviated by the arrangement of the cutting mechanism.

Other objects relate to consideration of economy of production, durability in use, and convenience in operation of the several mechanisms or parts entering into the construction of elements and the above defined general organization of said elements.

As hereinafter pointed out in the claims some of the novel features of the present invention reside in certain coöperative relationships existing between certain of the elements, of which the disclosed constructional embodiments are merely illustrative rather than definitive, while other features reside in the general organization of such elements; and still other features reside in the constructional characteristics of the particular elements herein disclosed as the preferred instrumentalities through which to realize such coöperative relationships and general organizations.

One embodiment of the subject matter of

the specification is shown by way of illustration in the accompanying drawings, in which:

55

Figure 1 is a fragmentary longitudinal section in elevation of the cutting mechanism of my improved machine;

60

Fig. 2 is a horizontal section taken through the straw guides of the machine;

Fig. 3 is a transverse section in elevation through the machine showing the mounting of the cutting mechanism; and

Fig. 4 is a section on line 4—4 of Fig. 1.

Similar characters of reference are employed in all of the above described views to indicate corresponding parts.

Referring now more specifically to the several figures of the said drawings, my improved cutting machine may be said to embody the usual bed indicated in its entirety by the numeral 1, the upper face of which is substantially flat and has arranged thereon a secondary bed plate 2 provided with a pair of longitudinally extending relatively 70 parallel guide ways or tracks 2', the said secondary bed plate being secured to the upper face of the bed 1 through the medium of bolts 3, which bolts are passed through apertured lugs 4 formed upon the outer sides 80 of the secondary bed plate 2, the bolts, as will be obvious, being engaged with the machine bed 1. Movable top plates 5 are arranged upon the upper portions of the guide tracks 2' and are secured in position by 85 means of a plurality of locking bolts 6, the said bolts being carried by the respective guide tracks and have turned into engagement with their threaded extremities, suitable locking nuts. A bearing block 7 is secured to the under face of the upper portion of the machine bed 1 by set screws 8 or the like and serves as means for rotatably supporting a large spiral gear 9, the said gear being provided with a stub shaft 10 which 95 is seated within the bearing opening of the block 7. A portion of the outer end of the bearing block 7 is cut away, as at 11, the purpose of which will be presently apparent.

A drive shaft 12 is mounted within bearings formed upon the lower portion of the machine bed as indicated by the numeral 13 and extends from a suitable prime mover. A small spiral gear 14 is keyed to the said

drive shaft and meshes with the spiral gear 9, thus, causing the same to be rotated when the shaft 12 receives its driving motion.

A vertically disposed bearing sleeve or pillar 15 is passed through a suitable opening in the top portion of the machine bed 1 and is secured in position thereupon by means of an annular flange 16, which flange is provided with a plurality of circularly disposed openings, whereby set screws 17 may be turned into engagement with the same and also with the adjacent portion of the machine bed. An offset bearing arm 18 is formed integral with the upper extremity 10 of the bearing sleeve or pillar 15 and has arranged therein, preferably, intermediate its ends, a suitable bearing opening, which I shall indicate by the numeral 19 and shall hereinafter more fully describe the purpose 15 of the same. A shaft 20 is mounted within the bearing sleeve or pillar 15 and carries upon its opposite extremities a small bevel gear 21 and a somewhat larger bevel gear 22, the latter, as will be noted, being arranged 20 upon the upper extremity of said shaft 20. A bevel gear 23, of suitable size is keyed to the drive shaft 12 and meshes with the bevel gear 21, consequently, imparting rotary motion to the vertically disposed shaft 20 upon 25 similar movement of the said drive shaft.

Referring now to the improved cutting mechanism of my machine, I mount for reciprocal movement upon the guide tracks 2' a frame 24, securing the same upon the 30 said guide tracks by means of the removable top plate 5. The frame 24 carries thereon a secondary and vertically disposed frame 25, which, has a portion of the inner faces of the sides thereof grooved as at 26 in order that 35 a cutter supporting head 27 having guide lugs formed thereon and adapted for engagement with the grooves 26 may be received by the same. The lower portion of the head 27 is bifurcated as at 28 and normally rests or bears upon the frame 24 to 40 permit connection of means for raising and lowering the same at the proper intervals, which means will be more fully described hereinafter. A brace arm 29, may be and 45 preferably is formed integral with the frame 24 and extends diagonally upward into proximity of the secondary frame 25, whereat, it is engaged with the sides of the vertical or secondary frame 25, thus, trussing the 50 same. A straw guiding element 31, is arranged upon the upper extremity of the frame 25 and may be, if so desired formed integral therewith. Said guide is provided with a longitudinally extending substantially funnel shaped opening 32, through 55 which the continuous tube to be cut is adapted to pass. A second guide element 33 having a downwardly bent portion, which portion is provided with an opening therein 60 aligned with the reduced portion of the open-

ing 32, is secured to the guide element 31 by means of set screws 34 and will serve as means for bracing the tube during severing of the same into uniform lengths. It is to be noted, that the downwardly bent portion 70 of the guide 33 is arranged in spaced relation from the guide element 31. Within the frame 24, there is formed a slot of sufficient size to permit the mounting of an idler 36 therein, while to one side of the said idler, 75 there is formed a second slot, this slot being arranged in proximity to the lower portion of the vertically disposed frame 26 and receiving therethrough the lower portion of a roller 35, the said roller being journaled 80 within suitable bearings in the lower extremity of the bifurcated portion 28.

With a view toward providing means whereby a reciprocating motion may be imparted to the frame 24, a bearing pin or 85 roller 37 is arranged eccentrically of the spiral gear 9 and is adapted to be received within an elongated slot 60 formed in a rock arm 38, which rock arm is pivotally supported upon a suitable portion of the machine bed 1, as at 39 and extends upwardly to a point above the spiral gear 9, whereas it is provided with a forked or bifurcated portion 40, the said portion embracing the idler 36, carried by frame 24. Hence, upon 90 rotation of the spiral gear 9, it will be appreciated, that the rotary motion thereof will be converted into a reciprocating motion by means of the rock arm 38 and through the medium of the connection of 100 the said rock arm with the frame 24, a similar motion will in turn, be imparted thereto, consequently, causing the reciprocation or sliding of the said frame together with the vertically disposed frame 25 carried thereon. 105

A longitudinally extending driven shaft 41 is passed through the bearing opening 19 formed in the arm 18 and extends forwardly and is connected by a universal joint 42 with an arbor 41' journaled in a bearing 110 block 27' arranged in the head 27. A beveled gear 43 is splined to the driven shaft 41 and a laterally extending collar 44, extends into the bearing opening 19 and has its opposite side portions engaged by horizontally arranged bearing screws 45. A locking nut 46 is arranged upon the outer end of the bevel gear hub and serves as means for positively preventing undue lateral movement of the bevel gear 43. By so arranging 115 the bevel gear 43 within the bearing opening 19, it is evident, that oscillatory movement of the driven shaft 41 is permitted. Upon the forward extremity of the arbor 41', a reduced portion 47 is formed and receives 120 thereupon a disk cutter 48, the said cutter having portions of its opposite faces engaged by annular washers 50 and being secured upon the reduced portion 47 by means of a locking nut 51, which locking nut is 125

turned into engagement with the threaded extremity of the reduced portion 47. As disclosed, the drive shaft 41 is mounted for oscillatory movement, and the arbor 41' is 5 adapted to move vertically within the frame 25, thereby permitting the cutting disk to be moved past the reduced portion of the opening 32 within the straw or tube guiding element 31, whereby, to allow proper cutting engagement of the same.

To intermittently bring the disk cutter 48 into engagement with the tube to be cut or severed, a second roller 52 is mounted eccentrically of the spiral gear 9 and in spaced 15 relation from the roller 37 and is adapted to be intermittently engaged with a lever arm or trip lever 53, the said lever carrying a shoe 54 upon the free portion thereof and being pivotally engaged with the secondary bed plate 2 as at 55. Thus, as the roller 52 engages the trip lever 53, the said lever will, due to the size or diameter of said roller, be moved upwardly into engagement with the roller 36 carried upon the lower portion 20 of the cutter head 27, thereby, momentarily raising the same and moving the disk cutter 48 into cutting engagement with the tube. By reason of the brief engagement of the roller 52 with the trip lever 53, it will 25 be appreciated, that the moving of the disk cutter 48 to cutter engagement is but momentary and that when the roller 52 is disengaged from the trip lever 53, the said cutter will be permitted to drop or return 30 to its inoperative or lowermost position. As a means for insuring a quick return of the cutter, I preferably provide in the upper end of the bearing block 27' a bore 56 and insert therein a spiral spring 57 which is 35 adapted to bear against the underside of the guide element 31. If it is desirable to effect a slight vertical adjustment of the cutter 48 relative to the opening in the straw guide shims 58 may be slid in between the 40 head and bearing block as disclosed. During the engagement of the disk cutter 48 with the tube being fed or directed through the guide element 31, it is evident that movement of the said disk cutter with the tube 45 is necessary to prevent tearing of the same and to insure an even and perfect cut of the same. Therefore, by providing the reciprocating frame 24, it is evident, that as the disk cutter 48 is moved into engagement with the tube, the same will also travel at the same speed with the tube for a short 50 distance, until the cutting operation has been completed. As the one cutting opera-

tion is completed the frame 24, will by its reciprocal mounting, be instantly returned 60 to its initiative starting position ready for a second or further cutting operation.

A second straw guiding element 59 is mounted within a suitable opening formed in the upper portion of the arm 18 and is 65 provided with a funnel like opening therethrough, complementary to the opening 32 in the guide element 31. Thus, the continuous tube will be properly directed into engagement with the funnel shaped opening 70 of the guide element 31.

As many changes could be made in the above construction and many apparent widely different embodiments of this invention could be made without departing 75 from the scope thereof, it is intended that all matter contained in the above description or shown in the accompanying drawings shall be interpreted, as hereinbefore intimated, as illustrative and not in a limiting sense. It is also to be understood, that the language used in the following claims is intended to cover all of the generic and specific features of the invention herein described and all statements of the same, 80 85 which, as a matter of language, might be said to fall therebetween.

I claim:

1. The combination with a main frame, a horizontally and a vertically reciprocating frame, and a flexible reciprocating shaft carrying a cutter disk, of a wheel, two rollers carried thereby, a slotted bifurcated lever in the slot of which one of the rollers operates, rollers carried by both the horizontal and vertical reciprocating frame, one of said rollers operating in the bifurcated portion of the lever and a trip lever in position to be operated by one of the rollers on the wheel which in turn engages the roller 90 95 100 on the vertically reciprocating frame to force the cutter disk laterally to cut any article in its path at a predetermined time.

2. The combination with two frames, a main frame, a bearing block, a flexible shaft 105 rotatably supported in the main frame and the bearing block and reciprocable in said main frame, a cutter disk on said flexible shaft, a roller carried by each movable frame, of a wheel having means thereon 110 and operated thereby to cause the rollers on the two movable frames to be engaged at predetermined intervals to cause said frames to move in their prescribed paths.

In testimony whereof I affix my signature. 115
SYLVESTER B. McGUNIGAL.
